(57) **CLAIM**

I claim the ornamental design for the hanging apparatus, as shown and described.

DESCRIPTION

FIG. 1 is a perspective view of the design for a hanging apparatus showing the hanging member extended outwards from the body.

FIG. 2 is a side view of the left side of the hanging apparatus of FIG. 1 with the hanging member extended outwards from the body.

FIG. 3 is a rear elevation view of the hanging apparatus of FIG. 1 with the hanging member extended outwards from the body.

FIG. 4 is a front elevation view of the hanging apparatus of FIG. 1 with the hanging member extended outwards from the body.

FIG. 5 is a side view of the right side of the hanging apparatus of FIG. 1 with the hanging member extended outwards from the body.

FIG. 6 is a top plan view of the hanging apparatus of FIG. 1 with the hanging member extended outwards from the body.

FIG. 7 is a bottom plan view of the hanging apparatus of FIG. 1 with the hanging member extended outwards from the body; and,

FIG. 8 is a perspective view of the hanging apparatus of FIG. 1 showing the hanging member recessed into the body.
